Primary Examiner — Jack Reickel*Assistant Examiner* — Keith J Wilson(74) *Attorney, Agent, or Firm* — Law Office of Sam Sokhansanj PLLC(57) **CLAIM**

The ornamental design for a toy railroad track adapter, as shown and described.

DESCRIPTION

FIG. 1 illustrates a perspective view for one non-limiting exemplary embodiment of a toy railroad track adapter. FIG. 2 illustrates a rear view of the toy railroad track adapter of FIG. 1.

FIG. 3 illustrates a front view of the toy railroad track adapter of FIG. 1.

FIG. 4 illustrates a right side view of the toy railroad track adapter of FIG. 1.

FIG. 5 illustrates a left side view of the toy railroad track adapter of FIG. 1.

FIG. 6 illustrates a top view of the toy railroad track adapter of FIG. 1.

FIG. 7 illustrates a bottom view of the toy railroad track adapter of FIG. 1; and,

FIG. 8 illustrates a perspective view for another non-limiting exemplary embodiment of a toy railroad track adapter. The broken lines show portions of the toy railroad track adapter which form no part of the claimed design.
